UNITED STATES PATENT OFFICE.

THOMAS J. AVERY, OF ALBIA, IOWA.

COMBINATION SCRAPER, CHARGER, AND TAMPER.

1,421,358.

Specification of Letters Patent. Patented July 4, 1922.

Application filed July 15, 1921. Serial No. 484,975.

To all whom it may concern:

Be it known that I, THOMAS J. AVERY, a citizen of the United States, and a resident of Albia, in the county of Monroe and State of Iowa, have invented a new and useful Improvement in Combination Scrapers, Chargers, and Tamers, of which the following is a full, clear, and exact description.

My invention relates to improvements in combination scrapers, chargers and tamers of the type of construction disclosed in my prior application on account of which Letters Patent of the United States, No. 1379435 was issued to me on May 24, 1921, and it consists in the combinations, constructions and arrangements herein described and claimed:

An object of my invention is to provide a device of the character described having a charging barrel of uniform diameter and a coupling member having a diameter not greater than that of the barrel for connecting the latter with an operating rod, whereby an explosive charge can be effectively tamped in a bore or hole in the face of the mine wall without any part of the charge being withdrawn when the charging barrel is retracted.

A further object of my invention is to provide a device of the character described that is relatively simple in construction and operation and thoroughly effective for the purpose for which intended.

Other objects and advantages will appear in the following specification, and the novel features of the invention will be particularly pointed out in the appended claims.

My invention is illustrated in the accompanying drawings, forming part of this application, in which—

Fig. 1 is a plan view of the device,

Fig. 2 is a longitudinal section through the device, portions thereof being shown in elevation,

Fig. 3 is an end view of a portion of the device,

Fig. 4 is a detail, partly in section, of a fragmentary portion of the mechanism shown in Fig. 1.

In carrying out my invention, I provide a substantially cylindrical barrel or charging tube 1. The barrel or tube 1 has concentric inner and outer walls, the outer wall being uniform in diameter for its entire

length. A coupling ring 4 has an outer diameter equal to that of the barrel 1 and the outer wall thereof is cut away at 5 to provide an end portion 2 adapted to fit into the bore of the barrel 1 and to define a shoulder 6 adapted to abut the adjacent end wall of the barrel 1. The end portion 2 of the ring 4 may have a friction tight connection with the barrel 1 and is additionally secured to the latter in any suitable manner as by being soldered thereto. The inner wall of the coupling ring 4 has a diameter less than that of the inner wall of the barrel 1 and projects inwardly beyond the latter to provide an annular stop member 7, as best seen in Fig. 4. The ring 4 is formed with integral rearwardly extending arms 8—8 which are bent inwardly toward one another intermediate their length so that the end portions thereof are substantially parallel with one another and are adapted to straddle a co-operating coupling member 9. The latter is rigidly secured to a tube 10 in axial alignment with the latter.

The coupling member 9 has its outer wall flattened at diametrically opposed points to engage with the parallel portions of the arms 8—8. Pivot pins 11—11 are projected through registering openings in the parallel portions of the arms 8—8 and the flattened portions of the wall of the coupling 9, whereby the barrel 1 may be swung 90° about the axis of the pivot pins 11—11 and is held against further movement by means which will be hereinafter described.

The coupling member 9 is provided with a bore 12 which is enlarged at 13, as shown in Fig. 4. A rod 14 is arranged to enter the bore 12 and is provided with a reduced portion 15 having straight opposite walls 16 and 17 and being projected into a slot 18 in the adjacent end of a plunger stem 19. A pivot pin 20 secures the reduced portion 15 to the plunger stem 19, as shown. The plunger stem 19 is formed with parallel sides 21—21 adapted to slidably contact with parallel portions 22—22 of the inner walls of the bore 13, whereby the plunger stem is held against rotation, but is permitted to move upwardly about the axis of the pivot pin 20 through an opening 23 extending from the inner to the outer walls of the coupling member 9, as shown. The rod 14 carries a scraper 24 at its end remote from the

barrel. The scraper 24 has a shank or stem secured to the rod 14 and this stem has an outwardly projecting stud 25 adapted to cooperate with a slot 26 in a retaining sleeve 5 27 that is connected with the tube 10, whereby the rod 14 may be locked against axial movement in the manner described in the aforesaid patent issued to me.

The plunger rod 19 is integral with a 10 plunger 28 arranged for reciprocation in the barrel 1. The plunger 28 constitutes the ejecting and tamping member of the device and the outer face thereof is therefore formed to provide a substantially plane surface 15 face.

From the foregoing description of the various parts of the device, the operation thereof may be readily understood. The stud 25 is moved axially to occasion a retraction 20 of the plunger 28 in the barrel 1.

The barrel 1 is then swung upwardly about an axis coinciding with the axes of the pivot pins 11-11 and the pivot pin 20 (see Figures 2 and 4) into a position at right angles 25 to the sleeve 10. The engagement of the sides of the plunger stem 19 with the contiguous side walls of the bore of the coupling member 9 will prevent the rotation of the barrel 1 about the axis of the rod 14. An 30 explosive charge is then placed within the barrel 1 and the latter is then moved into axial alinement with the tube 10 and may be projected into a bore or hole in a mine wall. The scraper member 24 can be 35 grasped conveniently when it is desired to move the rod 14 in the direction of its length and when the barrel 1 has been projected into the bore or hole in the mine hole, the scraper member 24 may be shoved forwardly 40 to occasion the ejection of the explosive charge from the barrel 1. The stud 25 is then moved along the slot 26 to lock the rod 14 to the tube or sleeve 10, and the device is operated as a unit to occasion the 45 tamping of the explosive charge in the hole in the mine wall. It is important to note that the outer wall of the barrel 1 is uniform in diameter for its entire length. Consequently, the device may be used in placing 50 an explosive charge in bores having a diameter but slightly greater than that of the barrel 1. The outer wall of the barrel 1 is smooth and there are no outwardly protruding parts to occasion the withdrawal of any 55 part of the explosive charge from the bore in the mine wall or to interfere with the functioning of the device as a tamping tool. The annular shoulder 7 provides a stop member which limits the movement of the 60 plunger 28 toward the coupling member 9 and insures the alinement of the axis of the pivot pin 20 with the axes of the pivot pins 11-11. It will be observed that the arms 8-8 are provided with alined openings 3-3.

65 These openings 3-3 are adapted to register

with alined openings 29-29 through the walls of the coupling member 9 when the barrel 1 has been moved into the position indicated by the dotted lines in Fig. 2. The rod 14 may be moved until the plunger 70 shank 19 is positioned as indicated by the dotted lines in Fig. 2, at which time an opening 30 through the plunger shank 19 is in registry with the openings 3-3, 29-29. A cotter pin 31 may be projected through the 75 registering openings to prevent axial movement of the rod 14 relative to the sleeve 10. The rod 14 is thus held in extended position and in consequence drillings or the like may be removed from holes of greater depth than 80 is possible when the parts of the device are in the position illustrated in Fig. 1, the effect of securing the plunger shank in the position indicated by the dotted lines in Fig. 2 being to lengthen the device. 85

I claim:

1. In a device of the character described, a tubular charge receiving member of uniform outside diameter for its entire length, a coupling ring secured to the charge receiving member at one end of and in axial alinement with the latter, said coupling ring having an outside diameter substantially equal to that of the charge receiving member, an inside diameter less than that of the charge receiving member, and being formed with a pair of inwardly offset arms, a second tubular member, a second coupling member carried at one end of the second tubular member and pivotally supported between the 90 arms of the first named coupling member, a rod slidable in the second named tubular member, and a plunger slidably disposed in the charge receiving member and provided with a shank pivoted at its end to the adjacent end of the said slidable rod. 100

2. In a device of the character described, a tubular charge receiving member of uniform outside diameter for its entire length, a coupling ring secured to the charge receiving member at one end of and in axial alinement with the latter, said coupling ring having an outside diameter substantially equal to that of the charge receiving member, an inside diameter less than that of the charge receiving member, and being formed with a pair of inwardly offset arms, a second tubular member, a second coupling member carried by the second tubular member and being pivoted intermediately between said 110 arms, said second named coupling member being provided with a bore axially alined with the bores of the tubular charge receiving member and of the second named tubular member, and being provided with a slot 115 extending inwardly from the end thereof adjacent to the charge receiving member, portion of the opposite inner wall of the second named coupling member being straight and parallel, a rod slidable in the second 120 tubular member and being provided with a slot 125 extending inwardly from the end thereof adjacent to the charge receiving member, portion of the opposite inner wall of the second named coupling member being straight and parallel, a rod slidable in the second 130

named tube and projecting through the second named coupling member, and a plunger slidably disposed in the charge receiving member and having a shank pivoted at its 5 end to the end of the rod, said shank being adapted to co-act with the slot in the second named coupling member to permit a limited movement of the charge receiving member about an axis coinciding with the axes of the pivot pins connecting the said coupling members and for preventing rotation of the charge receiving member relative to the second named coupling member.

THOMAS J. AVERY.
